UNITED STATES PATENT OFFICE.

ARTHUR R. MOSLER, OF NEW YORK, N. Y., ASSIGNOR TO A. R. MOSLER & CO., OF YONKERS, NEW YORK, A CORPORATION OF NEW YORK.

SPARK-PLUG.

1,257,729.

Specification of Letters Patent. Patented Feb. 26, 1918.

Application filed January 16, 1914. Serial No. 812,569.

To all whom it may concern:

Be it known that I, ARTHUR R. MOSLER, a citizen of the United States, and resident of the borough of Manhattan, in the city and State of New York, have invented a new and useful Improvement in Spark-Plugs, of which the following is a specification.

My invention relates to an improvement in spark plugs and has for its object to provide certain improvements in the construction whereby a priming charge may be conveniently introduced into the cylinder of an engine in close proximity to the electrodes of the spark plug.

15 A further object is to provide a spark plug with a priming device which is practical, effective, and one which will serve to keep the points of the electrodes clean.

A practical embodiment of my invention 20 is represented in the accompanying drawings, in which

Figure 1 represents a plan view of my improved spark plug,

Fig. 2 represents a side elevation of the 25 same,

Fig. 3 represents a longitudinal section taken in the plane of the line A—A of Fig. 2, showing the priming device closed,

Fig. 4 represents a similar view showing 30 the priming device open, and

Fig. 5 represents in detail side and end views of the operating valve.

The tubular base of the plug is denoted by 1 and is provided with the usual screw 35 threaded portion 2 on its inner end. The base is also provided with an annular seat 3 at the outer end of the bore 4.

The outer end of the base is provided with an outwardly extended screw threaded portion 5 of reduced diameter for receiving a cap 6.

An insulating block 7 is provided with an annular flange 8, a tapered inner portion 9 and an outer portion 10.

45 An electrode 11 is centrally located in the block 7, and is secured within said block by any well known and approved means. The electrode 11 is also provided at its outer end with the usual thumb nut 12 for securing an electric wire to the plug. A gasket 13 of some suitable packing material is interposed between the seat 3 and the under side of the flange 8 on the insulating block.

A gasket 14 of some suitable packing material is interposed between the cap 6 and

the upper side of the flange 8 on the insulating block. The cap 6 when in position on the screw threaded portion 5 will clamp the flange 8 between the gaskets 13 and 14, thereby forming a gas tight joint between 60 the base and the block, and will allow the block to expand slightly under the influence of heat to which the plug is subjected.

The top of the base 1 is provided with an annular recess 15 surrounding the screw-threaded portion 5, and is also provided with a passage 16 in communication with the bore 4, through a port 17 in the base, opened or closed by a needle valve 18. This valve 18 is threaded into a bushing 19, 70 which is screwed into the base 1, and is provided with a passage 20 which registers with the passage 16.

A weighted handle 21 is secured to the outer end of the valve 18 for conveniently 75 opening and closing the valve. The handle, being weighted, tends, when the valve is closed, to hold it in its closed position.

The valve 18 has a cutaway portion 22 which, when the valve is open, as shown in 80 dotted lines in Fig. 2, and in solid lines in Fig. 4, will leave an unobstructed communication from the annular recess 15 through the passages 16, 20, and valve port 17, to the tubular bore 4.

85 To prime an engine equipped with my improved plug, a charge of liquid hydrocarbon is deposited in the annular recess 15, which charge will, when the valve 18 is opened, flow through the passages 16, 20, 90 90 valve port 17, into the bore 4, and will then pass down the block 7 and the electrode 11.

It will thus be seen that, by introducing a priming charge into the cylinder through the bore 4, the electrode terminals, as well 95 as the inner portion of the block, will be kept clean.

What I claim is:

1. In a spark plug, a base provided with a tubular bore therethrough, an insulating block therein, having an electrode, an annular priming recess surrounding said bore, a passage leading from said recess to the bore and a valve for opening and closing said passage.

100 105 110 2. In a spark plug, a base provided with a tubular bore therethrough, an insulating block therein having an electrode, an annular priming recess surrounding said bore, a passage leading from said recess to the bore

and block, and a valve for opening and closing said passage.

3. In a spark plug, a base provided with a tubular bore therethrough, an insulating block therein having an electrode, an annular priming recess surrounding said bore, a bushing secured in said base, a passage leading from the said recess to the bore and block, and a valve threaded in said bushing adapted to open and close said passage.

4. In a spark plug, a base provided with a tubular bore therethrough, an insulating block therein having an electrode, an outwardly extending exteriorly screw threaded portion, a cap therefor for securing said block to the base, an annular priming recess surrounding said portion, a passage leading from said recess to the bore and block, and a valve threaded in the base for opening 20 and closing said passage.

5. In a spark plug, a base provided with a tubular bore therethrough, an insulating block therein having an electrode, an outwardly extending screw threaded portion, a cap therefor for securing said block to the base, an annular priming recess surrounding said portion, a bushing secured in said base, a passage leading from said recess through the bushing, to the bore and block and a 30 valve threaded in said bushing adapted to open and close said passage.

6. In a spark plug, a base provided with a tubular bore, an outwardly extending exteriorly screw threaded portion, an annular

priming recess surrounding said portion, a bushing secured in said base having a passage in communication with the bore, a passage leading from said recess to the passage in the bushing, and a valve threaded in said bushing provided with a cutaway portion 40 adapted to coact with the passage in the bushing for opening communication from the recess to the bore.

7. In a spark plug, a base provided with a tubular bore, an outwardly extending exteriorly screw threaded portion, an annular priming recess surrounding said portion, a bushing secured in said base having a passage in communication with the bore, a passage leading from said recess to the passage 50 in the bushing, a valve threaded in said bushing provided with a cutaway portion adapted to coact with the passage in the bushing for opening communication from the recess to the bore, and a weighted handle for 55 manipulating the valve, said handle tending by gravity to hold the valve open when on one side of its center and closed when on the opposite side.

In testimony, that I claim the foregoing 60 as my invention, I have signed my name in presence of two witnesses, this eighteenth day of December, 1913.

ARTHUR R. MOSLER.
